LABAN HEATH, OF BOSTON, MASSACHUSETTS

Letters Patent No. 66,387, dated July 2, 1867.

MODE OF DETECTING COUNTERFEITED BANK-NOTES, &c.

The Schedule referred to in these Letters Patent and making part of the same.

TO ALL WHOM IT MAY CONCERN:

Be it known that I, LABAN HEATH, of Boston, in the county of Suffolk, and State of Massachusetts, have invented a new and useful improvement in the Art of Detecting Counterfeit Bank-Notes; and I do hereby declare that the following is a full, clear, and exact description of the same, reference being had to the annexed drawings, making part of this specification, in which—

Figure 1 is a representation of several genuine vignettes used in printing national bank-notes of the denominations of \$10, \$20, \$50, and \$100, and

Figure 2 is a representation of one-half of the engravings printed on the back of the \$10 and \$20 national bank-notes.

Counterfeited bank-notes are to be detected by a comparison of the genuine and counterfeited notes. As but comparatively a few persons are at all times in possession of notes of all the various denominations, in order to enable them to make the necessary comparison it is desirable that they may be put in possession of at least a portion of all the genuine notes in circulation. To print all of any of the notes would be dangerous, as affording advantages to counterfeiters, enabling them to transfer such impressions. The same objection would be to the use of perfect impressions of the whole of any of the parts comprising the notes. To obviate this objection I propose to print upon clear, white paper, impressions of only a part of the notes of each denomination from duplicates of the original dies and plates, first cutting from such dies or plates a portion thereof, which may be done, as shown in fig. 2, by using only one-half of the plate, or, as shown in fig. 1, by cutting out of the die or plate a section. The portion printed will thus be perfect and sufficient for the purposes of comparison, but being imperfect, could not be used by counterfeiters for the purpose of printing the entire figure, die, or plate, as it would be necessary to add the parts thus removed, which would be represented on the impression in ink of the same color as that used in making the impression in fig. 1, where a section is removed. By the use of duplicates of the genuine dies or plates thus mutilated, I am enabled to place, cheaply, in the hands of the people, all that is necessary for making comparisons with the counterfeits, and at the same time to avoid the danger of an improper use being made of such impressions by counterfeiters.

What I claim as my invention, and desire to secure by Letters Patent, is—

The mode of detecting counterfeit bank-notes by means of impressions made from duplicates of parts of the genuine dies or plates mutilated, substantially in the manner set forth.

In testimony whereof I have signed my name to this specification in the presence of two subscribing witnesses.

LABAN HEATH.
